ASH TRAY

Alvin A. Scheuerlein, 11 Crawford Ave., Oxford, Mich.

Filed May 9, 1960, Ser. No. 60,494

Term of patent 14 years

(Cl. D85—2)

Fig. 1 is a top plan view of an ash tray showing my new design;

Fig. 2 is a sectional view taken on the line 2—2 of Fig. 1;

Fig. 3 is a side elevational view; and

Fig. 4 is a bottom plan view.

I claim.

The ornamental design for an ash tray, substantially as shown.
